[57] ABSTRACT

A holder for a mineral mining cutter pick having a shank arranged for receipt in a socket in the holder, wherein the holder has a latch comprising a loop member arranged to surround a tool shank in the holder, and at least one resilient member e.g. of rubber co-operating with a part of the loop member to urge the loop member into engagement with the tool shank to resist removal of the shank from the socket.

TOOL RETAINING MEANS

This application is a continuation-in-part of my co-pending application Ser. No. 18,477, filed Mar. 11, 1970, for TOOL RETAINING MEANS and now abandoned.

The invention relates to a holder for mounting a shanked tool and more particularly, but not exclusively, to a holder having a socket for receiving a shanked cutter tool for use in a mineral mining machine.

According to the invention there is provided a holder having a socket for receiving a shanked tool, the holder having a resilient latch for retaining the shank in the socket, the latch comprising a member having parts disposed on opposite sides of the socket and connected by an intermediate portion or portions, at least one of which parts resiliently biases an opposite part towards and to lie at least partly in the socket, whereby on inserting a shank into the socket said opposite part engages the shank so as to retain it in the socket.

Preferably, resilient means is disposed between the first-said part of the latch member and the holder.

The latch member preferably comprises an endless member mounted to surround a shank in the socket.

Preferably the endless member is disposed in a recess formed in the wall of the socket and surrounding the socket. In one construction the recess is in the form of a slot extending through the holder from one side to the other. The slot may be disposed normal to the longitudinal axis of the socket or may be at an angle thereto. The resilient member may be of elastomeric material and is preferably arranged to surround a portion of the endless member. The resilient member is preferably disposed in a cavity in the holder.

The invention also provides a body defining a socket and adapted to receive a resilient latch for use in the combination defined above.

The invention further provides a resilient latch adapted to be used in a holder as set out above.

The invention is diagrammatically illustrated by way of example in the accompanying drawings in which:

FIG. 1 is a side elevation of a first embodiment of holder in accordance with the invention;

FIG. 2 is a sectional elevation of the holder of FIG. 1, taken on the line B — B of FIG. 1 and with a latch mounted therein;

FIG. 3 is an end elevation in the direction of arrow A of FIG. 1;

FIGS. 4a and 4b are respectively a plan view, and a sectional elevation on the line C — C of FIG. 4a through part of a resilient latch for use in the holder shown in FIGS. 1 to 3;

FIGS. 5a and 5b show respectively a side elevation and end elevation of a further part of the resilient latch shown in FIGS. 4a and 4b;

FIG. 6 shows a shanked cutter tool suitable for use in a holder as shown in FIGS. 1 to 3;

FIG. 7 is an end elevation of a second embodiment of holder in accordance with the invention;

FIG. 8 is a sectional side elevation on the line D — D of FIG. 7;

FIG. 9 is a plan view of the holder shown in FIGS. 7 and 8;

FIG. 10 is a side elevation of a third embodiment of holder in accordance with the invention;

FIG. 11 is a plan view of the holder shown in FIG. 10;

FIG. 12 is a sectional side elevation on the line E — E of FIG. 11 and with a latch mounted therein;

FIG. 13 is a side elevation of a latch suitable for use in the holder shown in FIGS. 10 to 12;

FIG. 14 is a plan view of the latch shown in FIG. 13;

FIG. 15 is a plan view of a modified latch suitable for use with the holders shown in FIGS. 1 to 3 or 7 to 9;

FIG. 16 is a section on the line F — F of FIG. 15, and

FIGS. 17 to 19 are respectively a side elevation, a cross-sectional plan view and a cross-sectional side elevation of a further modified arrangement.

Referring to FIGS. 1 to 6 of the drawings a holder for a coal cutter pick comprises a block 1 formed with a rectangular socket 2 extending therethrough from its upper to its lower surface. Midway between the upper and lower surfaces of the block a transverse slot 3 extends from one side of the block to the other and intersects the socket 2. To assist in the machining of the slot, a hole 18 is first bored through the block. At one end 15 the block is formed with a generally cylindrical recess 4 which communicates with the socket 2 via the slot 3.

A substantially rectangular endless member 5 is disposed loosely in the slot 3 so as to surround the socket 2 but with an end portion 6 thereof extending into the socket. An end portion 7 of the member 5 opposite the end portion 6 is mounted in a resilient bush 8 (preferably of neoprene) which is a tight fit in recess 4. Intermediate portions or limbs 13 connect the end portions of the member 5. The resilient bush 8 is generally cylindrical in shape and is formed with a diametrically disposed bore 9 arranged to receive the portion 7 of the endless member 5. In addition the sides of the resilient bush are relieved at 10 to receive the intermediate portions 13 of the endless member. The resilient bush is also formed with a slot 11 communicating with the bore 9, which slot can be distended to permit insertion of an endless member into the resilient bush. Alternatively the bush may be bonded or moulded round the endless member. The endless member 5 and the resilient bush 8 forms a latch by means of which a pick 12 can be resiliently retained in the holder.

As shown in FIG. 6 the coal cutter pick 12 is formed with a hard cutter tip 13 and with a shank portion 14 which is arranged to be received within the socket 2 of the holder 1, shoulders 15 on the cutter pick limiting movement of the pick into the socket. The shank 14 is formed with a recess 16 and is chamfered at 17 for the purposes to be described below.

50 In use, a coal cutter pick is inserted into the socket in the holder until the chamfered end of the shank engages the portion 6 of the endless member and displaces the portion 6 of the endless member from the socket by compressing the resilient bush 8 so that the cutter pick can be fully inserted into the socket. When the shank is fully inserted the portion 6 becomes aligned with the recess 16 in the shank of the tool and thus snaps into the recess under the action of the resilient bush. In this manner removal of the cutter pick from the holder is hindered.

60 Accidental removal of the pick is also hindered by reason that a force tending to remove the pick from the holder will cause the endless member to ride up the inclined face of the recess 16 until the upper surface of the endless member contacts the underside of the slot 3, thus creating a wedging action resisting further movement of the tool.

Referring now to FIGS. 7 to 9 of the drawings there is shown a pick holder 1 which is generally similar to that described above with the exception that the slot 3 is closed at the sides of the holder and instead extends through the holder from end to end. The holder is arranged to receive an endless member 5 and a resilient bush 8, for example of the kind shown in FIGS. 4 and 5 of the drawings.

FIGS. 10 to 14 of the drawings illustrate a modified form of holder and resilient latch in which the slot 3 extends through the holder from side to side and in which the recess 4 also extends through the holder from side to side. The slot 3 is disposed at a shallow angle (e.g. 10°) to the normal to the axis of the socket 2. The inclined slot 3 enhances the wedging effect (referred to above) which occurs when a force tends to remove a pick from the socket.

In this embodiment the resilient latch comprising the endless member 5 and the resilient bush 8 is inserted into the holder sideways rather than endways as is the case in the arrangement described above. As can be seen in FIGS. 13 and 14 the endless member 5 is trapezoidal in shape and the resilient bush 8 is generally similar in construction to that illustrated in FIG. 5 except that the bush substantially wholly surrounds a part of each limb or intermediate portion 13 of the endless member.

In FIGS. 15 and 16 there is shown a modified form of resilient latch which may be used in place of the latch described in FIGS. 4 and 5 of the drawings. As best seen in FIG. 15 the elastomeric bush 8 is sandwiched between steel end plates 12. It has been found that the end plates 12 have the effect of imparting to the latch a more positive action by preventing undue and uncontrolled distortion of the bush.

In FIGS. 17 to 19 of the drawings there is shown a coal cutter pick holder arrangement generally similar to those described above. The holder 1 is formed with a pair of transverse recesses 4 extending there-through, the recesses being positioned one at each side of the socket 2. A slot 3 extends through the holder from one side to the other so as to intersect the socket 2 and to join the recesses 4. A pair of oppositely disposed projections 24 extending laterally of the holder are arranged in the vicinity of the slot 3.

The resilient latch 5 comprises a generally rectangular closed loop of metal, the opposite ends of which carry resilient bushes 8. The bushes 8 are cylindrical in form and are moulded onto the loop. The end 6 of the loop carries an oppositely disposed pair of fingers 23.

The latch is arranged to be disposed in the slot 3 to surround the socket in the holder, the resilient bushes 8 being disposed one in each of the recesses 4. The end 6 of the latch projects into the socket to form a detent for retaining the tool 12 in the holder, and the fingers 23 project from the sides of the holder.

When it is desired to insert a tool in the holder and/or remove a tool therefrom, a lever is engaged between the projections 24 and the fingers 23 and the latch is moved in the direction of the arrow B (FIG. 18) to compress the bushes 8, so as to remove the end 6 of the latch from the socket.

As the tool holder block is symmetrical, the latch can be inserted either way round so that the tool can be used to cut in either direction.

I claim:

1. A holder having a body formed with a socket for receiving a shanked tool and a resilient latch for retaining the shank in the socket, wherein the latch comprises a member having parts disposed on opposite sides of the socket and operatively connected by at least one intermediate portion, at least one of which parts resiliently biases an opposite part towards and to lie at least partly in the socket, whereby on inserting a shank into the socket said opposite part engages the shank so as to retain it in the socket, and resilient means being disposed between the said one part of the latch member and a portion of the body of the holder disposed between the socket and the said one part.
- 10 2. A holder according to claim 1, wherein the resilient member is of elastomeric material and is arranged to surround a portion of the endless member.
- 15 3. A holder according to claim 1, wherein the body defines a cavity in which the resilient member is disposed.
- 20 4. A holder according to claim 1 wherein the latch member comprises an endless member mounted in the body to surround a shank in the socket.
- 25 5. A holder according to claim 4, wherein the body defines a recess in the wall of the socket and surrounding the socket and in which the endless member is disposed.
- 30 6. A holder according to claim 5, wherein the recess in the body is in the form of a slot extending through the body from one side to the other.
- 35 7. A holder according to claim 6, wherein the wall of the slot is disposed at an angle to the normal to the longitudinal axis of the socket.
- 40 8. A holder having a body defining a socket for receiving a shanked tool, comprising a recess in the wall of the socket and surrounding the socket, an endless member received in the recess, a cavity communicating with the recess, a resilient member received in the cavity, the endless member and the resilient member together defining a resilient latch for retaining the shank in the socket and the resilient member resiliently biasing a part of the endless member towards and to lie at least partly in the socket, whereby on inserting a shank into the socket said part engages the shank so as to retain it in the socket.
- 45 9. A holder according to claim 8, wherein the endless member comprises a latching part, an oppositely disposed resiliently biased part and a pair of intermediate portions which join the two parts and wherein the resilient member is elastometric.
- 50 10. A holder having a body formed with a socket for receiving a shanked tool and a resilient latch for retaining the shank in the socket, the latch comprising a generally rectangular loop member which is mounted in the body to surround a shank in the socket whereby limbs of the loop are disposed on opposite sides of the socket and resilient means associated with an oppositely disposed pair of limbs of the loop member and biasing one of the limbs thereof to lie at least partly in the socket, whereby on inserting a shank into the socket said one limb engages the shank so as to retain it in the socket.
- 55 11. A holder as claimed in claim 10, wherein the resilient means comprises elastomeric members disposed one on each of the oppositely disposed pair of limbs.
- 60 12. A holder as claimed in claim 11, wherein the elastomeric members are cylindrical in form.

13. A holder as claimed in claim 11, wherein the elastomeric members are moulded on the said pair of limbs.

14. A holder as claimed in claim 11, wherein the body defines cavities extending therethrough for receiving the elastomeric members one on each side of the socket, the cavities being disposed transverse to the axis of the socket and transverse to the intended cutting direction of the tool, the body also being formed with a slot for accommodating the latch member, which slot extends through the holder from side to side, the slot joining the cavities and intersecting the socket.

15. A holder as claimed in claim 10, wherein the resilient latch comprises a pair of oppositely disposed fin-

gers arranged, in use, to project from opposite sides of the body, the fingers providing surfaces against which a lever can bear in order to displace the latch resiliently so that a tool shank can be inserted in, and removed from, the socket.

16. A holder as claimed in claim 15, comprising projections on the body disposed forwardly of the fingers in the cutting direction of the tool, to shelter the fingers against contact with obstructions which might otherwise cause accidental unlocking of the latch, and also to provide surfaces against which the lever can bear when removing and replacing the tool.
